AUTOMOTIVE VALVE CAP

Ted P. Nelson, Seattle, Wash.
(P.O. Box 66347, Burien, Wash. 98166)

Filed May 13, 1968, Ser. No. 11,900

Term of patent 14 years

Int. Cl. D12—14

U.S. Cl. D90—20

Fig. 1.

Fig. 3.

Fig. 2.

Fig. 4.

FIGURE 1 is a top plan view of an automotive valve cap showing my new design.

FIGURE 2 is a side elevational view thereof.

FIGURE 3 is a top perspective view thereof.

FIGURE 4 is a bottom perspective view thereof.

The dominant features of my design reside in the portions shown in full lines.

I claim:

The ornamental design for an automotive valve cap, substantially as shown and described.
